UNITED STATES PATENT OFFICE.

CARL A. MONSON AND HARRY GEARING, OF LOS ANGELES, CALIFORNIA, ASSIGNEES,
BY MESNE ASSIGNMENTS, TO HADLEY TAG & MACHINE CO., OF LOS ANGELES, CALI-
FORNIA, A CORPORATION OF CALIFORNIA.

TAG MAKING AND PRINTING MACHINE.

Application filed February 14, 1920. Serial No. 358,746.

To all whom it may concern:

Be it known that we, CARL A. MONSON, a citizen of the United States, and HARRY GEARING, a subject of the King of Great Britain, residing at Los Angeles, in the county of Los Angeles and State of California, have invented new and useful Improvements in Tag Making and Printing Machines, of which the following is a specification.

This invention relates to tag making and printing machines, that is to machines for forming, printing and discharging identification, shipping and similar tags, which, in the operation of the machine, in the performance of its several functions in sequence, are discharged from the machine in piles or stacks ready for storage or packing and shipment or other disposition. The invention contemplates the complete production of such tags from stock which is supplied in strip form, including the application of eyelets and reinforcement for the eyelets, the printing of the tags and their perforation if desired as well as the severing of the stock to produce units of single tags or of a plurality of tags as may be desired. We are aware that machines have been devised heretofore for performing certain of the steps incidental to the operation of our improved machine, but we are not aware that any machine has heretofore been devised capable of performing the complete sequence of acts last mentioned. Furthermore, we are not advised that any machine has heretofore been produced capable of carrying on the several steps or any of them incidental to the manufacture and printing of tags, that is, any machine operating rotatively. We are aware that certain of the steps have heretofore been carried on by the use of reciprocating machine members and elements, and these, as stated, only for performing certain of the functions but not all or any material number of same.

In accordance with the present invention, the machine as a single unit, is capable of long continued operation for the utilization of stock and material fed to it as the several steps of manufacturing and printing take place, and the machine is entirely automatic in operation, finally delivering the finished and printed tags in groups, which

are stacked up uniformly so as to be capable of packing in compact form.

The invention is not concerned in many of the details and parts of a machine, embodying the invention, but contemplates broadly the combinations and sub-combinations of parts and features, which parts and features as to their particular nature may be widely varied without departing from the general spirit and principles of the invention. In certain respects, invention resides in parts and sub-combinations which will be clearly described in the discussion of the general construction and operation of the machine, all as hereinafter set forth, shown in the drawing, and then finally pointed out in claims.

The invention has for further objects the provision of a machine of the character stated which will be relatively simple and inexpensive in construction when these factors are taken into consideration with positiveness in operation, capability of long continued operation without need of repair or replacement, durability, and general efficiency and serviceability. A further object of the invention is to provide a machine of the character stated which will be exceedingly rapid in operation and capable of turning out a large quantity of finished and printed tags in a given time period.

The invention consists in the novel and useful provision, construction, combination, relative arrangement, inter-relation and association of parts, members, features and elements, as well as the mode of operation of the same, all as developed in the specification and depicted in the drawing.

In the drawings:

Figure 1 is a diagrammatic side elevation of a tag making and printing machine constructed in accordance with the invention, certain of the parts being shown in full;

Figure 2 is a substantially similar longitudinal vertical sectional view of the machine shown diagrammatically in Figure 1;

Figure 3 is a fragmentary enlarged vertical longitudinal sectional view of the printing, numbering and perforating members of the machine, shown in Figures 1 and 2;

Figure 4 is a view similar to Figure 3, of the tag perforating and re-inforcement applying members of the machine, together

with eyelet applying member of the machine, and incidental features of the machine, shown in Figures 1 and 2;

Figure 5 is a fragmentary enlarged side elevation, partially diagrammatic and partially in section, of the tag accumulating and stacking members of the machine shown in Figures 1 and 2, upon an enlarged scale;

Figure 6 is a detail sectional view upon a large scale taken upon the line x^6-x^6 , Figure 2, looking in the direction of the accompanying arrows;

Figure 7 is an enlarged detail sectional view, particularly in elevation, taken upon the line x^7-x^7 , Figure 4, parts being broken away for clearness of illustration;

Figure 8, a detail longitudinal sectional view taken upon the line x^8-x^8 , Figure 7, and looking in the direction of the appended arrows.

Figure 9 is a similar view taken upon the line x^9-x^9 , Figure 4;

Figure 10 is a view similar to Figure 4, the eyelet supply and application means being omitted; and

Figure 11 is a detail view of a unit of four tags such as produced, printed, perforated, and provided with reinforcements and eyelets, in the operation of the machine shown in the other figures, and which unit group of tags is discharged from the accumulator to the stacker at the right end of Figures 1 and 2.

Corresponding parts in all the figures are designated by the same reference characters.

Referring particularly to the drawings, which show one form of the machine constituting the invention, from which form, as stated, many departures may be made in variation of construction, in adapting the machine to varying conditions in kinds and use of service, A designates a main frame which accommodates and supports the several leading elements and members of the machine, and their subsidiary features and agents, such members and elements in the main, reading from the left to right, of Figures 1 and 2, comprising a feed roll B of tag stock in strip form, an impression cylinder C about which such stock is passed, printing means D and E respectively by which various impressions or imprints may be made upon the tag stock as it traverses the impression cylinder numbering means F whereby the tag stock may be successively numbered in the portions thereof, which eventually constitute separate or distinct tags α , perforating means G operating to produce a line or series of perforations upon each tag portion of the stock, a secondary impression cylinder H with which cooperates reverse side printing means K for imprinting or impressing the reverse face of the stock at its several portions which become ultimately separate or distinct tags, feed means L and

M consisting of rolls for feeding re-inforcement material in strip form to the main tag stock, means N for applying the reinforcements taken from the means L and M to the main tag stock, and for punching or severing such reinforcement units as detailed by the means L and M, means O for feeding eyelets to a main tag stock, means P for punching the main tag stock and its reinforcements and applying the eyelets supplied by the means O, trimming and perforating (if desired) rolls or means Q, means R for severing the tag units or groups of units such as shown in Figure 11 after their impression, means S for receiving and accumulating such severed tags or groups of tags or tag units, and a stacker T to which such units or tag units are delivered intermittently from the accumulator S, and to which stacker such tag or tag units are fed in groups reversed end for end to insure an even stacking thereof.

The tag stock fed by the feed roll B is designated generally as b . The reinforcement stock is designated c as to the stock feed to the upper face of the tag stock b and d as to the stock feed from the roll M to the lower or reverse side of the tag stock b . V designates main drive shaft from which power is taken for the operation of the several members and features of the machine in any suitable or preferred manner, as will be outlined in certain departments of the machine, it being understood that such members as the numbering means F and the printing means D and E and the reverse printing means K are operated from such main drive shaft through any suitable form of operative connections, the same not being illustrated in detail, inasmuch as they are not concerned in the present invention. Likewise it will be understood that various transfer and idler rolls are utilized in the printing means and other elements, as indicated in the drawing, and to which special reference will not be made inasmuch as they also are not concerned in the invention and variation may be made in these respects as desired or as may be found preferable.

The impression cylinder c rotates upon a suitable transverse shaft 12, and is driven by a train of spur gears 13 and 14, and meshing miter gears 15 from the drive shaft V, the power being ultimately applied to such impression cylinder through an idler 16. The printing means D and the printing means E each comprise ink fountains 17 having a pick-up roll 18 from which the ink is transferred through distributing rolls and the like to printing cylinders 19 by which impression is directly made upon the tag stock b , as it passes over the impression cylinder C. Likewise, intermediate of the zones of operation of the printing cylinders 19, the numbering means F operates upon the stock 180

B, such numbering means including a printing cylinder 20, organized to successively number the successively presented portions of stock b, and receiving its ink through a 5 suitable train of transfer rolls and the like from a pick-up roll 21 immersed in an ink fountain 22. After the printing and numbering operations, the stock b passes to the perforating roll or means G, which operates 10 to produce suitable transverse perforations or a row of the same through the tag sections of the stock b. These perforations as well as the imprints of the printing means D and E are shown in Figure 11. Thence 15 the stock b passes to the reverse printing means K which includes similarly an ink fountain 23 and a train of distributing rolls and the like which convey the ink to the printing cylinder 24 which co-operates with 20 the reverse impression cylinder H, producing suitable impressions upon the reverse side of each portion of the stock b which ultimately becomes a separate or distinct tag. If desired, the perforating means G may 25 be dispensed with, and the trimming roll Q may be utilized both to trim the tags or tag units at their ends and also to perform the perforation, these details not being brought out in full showing in the drawings 30 as being obvious and subject to selection as desired or preferred.

The stock b printed upon both sides and numbered and perforated if desired, now passes to the means N for applying reinforcements at both sides of the stock b, such reinforcements being produced from the stock c and d, fed respectively about suitable guide rolls and contact with the stock b above and beneath the same. In order to apply the reinforcements and sever the reinforcement discs from the stock c and d, we employ upper and lower transfer cylinders 25 and 26 with which co-operate punching cylinders 27 and 28, having spring pressed 45 radially operating punches 29 which register with hollow dies 30, sunk into the transfer rolls 25 and 26, such hollow dies communicating with ducts 31 produced lengthwise of the transfer rolls 25 and 26 and communicating in a series by means of an annular duct 32, such annular duct being supplied by an inlet compressed air tube 33 which enters at one end an air chamber 35 rotatively received within a suitable annular 50 chamber in the periphery of the respective roll 25 or 26. With one of the longitudinal ducts 31 communicates a vacuum chamber 36 from which a vacuum pipe 37 leads to a suitable pump or vacuum unit. 34 designates an interrupted annular curve formed 55 in the roll 25 or 26 and which directly communicates with all of the ducts 31. The ducts 31 successively communicate with the interrupted annular duct 32, which is formed 60 between and spaced from the ends of the 65 duct 34. It results that, as the punch cylinders 27 and 28 operate to sever buttons or discs of reinforcement material from the stock c and d, the same are caused temporarily to adhere to the transfer rolls 25 and 26, 70 due to the suction influence exerted by the air withdrawn from the air chamber 36 through the suction pipe 37, and which suction is effective upon three of the ducts 31 75 at all times. The fourth of such ducts 31 is affected by the compressed air directed to it from the air chamber 35, and this takes place as to each duct when its respective hollow die is brought into registration with the tag stock b. As the transfer rolls 25 and 80 26 rotate in the respective directions indicated by the adjacent arrows in Figures 4 and 10, with their picked up and temporarily retained reinforcement discs or buttons, they come into registration with applicators 38 85 projecting radially from glue transfer cylinders 39, and to which applicators glue is supplied by wiping contact from a glue pick up roller 40, one for each cylinder 39, each such pick-up roller being immersed in a glue 90 fountain 41. The printed, numbered reinforced stock b now passes beneath a suitable compensating device e if desired, and around an idler roll f, and thence between two rolls 42 and 43, comprised within the means P 95 for punching the stock b and the reinforcements thereon and applying eyelets to the same. These eyelets are initially provided within an eyelet reservoir 44 having a rotated brush feed device 45, which serves to successively direct metal eyelets through a duct 46, down flat faced on to the stock b or an upper reinforcement disc or button thereon. 100

Immediately such eyelet is seized and brought with the registering reinforcement buttons between the roll 42 and 43, whereupon peripherally projecting punches 47 upon the roller 42 punch through the eyelets and the registering reinforcement discs and the stock b, eyelet after eyelet, the roller 43 having dies 48 limiting the thrust of the eyelet by such punches, and serving to upset and rivet over the metal of the eyelets and firmly bind them in place. An idler roll 49 and a tension roll 50 may be employed for causing a proper feed to the trimming rolls Q, so that the stock b, organized as described up to this point, shall properly register with said rolls. These cylinders 51 and 52 serve to trim the tags or tag groups at their ends and may perforate the same if desired, as previously mentioned. The trimmed stock as organized now passes to the means R for severing the stock as organized into the tags or tag groups. These means comprise a cylinder 53 which is provided with a plurality of transverse knives 54, certain of which may be of a limited length so as to but partially sever the stock between tags of a given group, as shown in 110

120

125

130

Figure 11, while the remaining knife may be of full width to entirely sever the organized stock and cut from it the group of four or other number of tags shown in Figure 11. 5 Such knives co-operate with a stationary knife or cutter bar 55, the cylinder 53 being disposed above the stock and the bar or knife 55 being disposed beneath it. The severed tags or tag group, now complete, may be delivered 10 from the machine at this point, or may be passed to the accumulator comprising an endless belt or conveyor 56, trained about suitable rolls 57, one of which is a driven roll fast upon transverse shaft 58, to 15 which is applied a loose clutch member 59 co-operating with a splined clutch member 60, operating lengthwise of the shaft 58, intermittently, by a rocker arm 61, one limb of which is actuated by a cam 62 upon a drive 20 shaft 63 operated through a train of gears 64, 65, 66 and 67, taking power from the main drive shaft V. The clutch member 59 receives its drive through a train of gears 68, 69, 70, which train of gears is driven 25 through a miter gear 71 from the main drive shaft V. Thus, the accumulator endless belt 56 is given an intermittent movement, serving to discharge from it each stack of a pre-determined number of tags or tag groups, 30 which are temporarily kept in place by a tension roller 72, such discharge taking place on to the stacker member T. This member consists of an inclined rotatable table 73, upon which the stacked tags or tag groups 35 are retained by the co-operation of an inclined wall 74. After each period of advancement of the accumulator belt 56 the standard or central support shaft 75 of the 40 rotating table 73 is given a half rotation in a bar 76 threaded to receive a threaded portion 76a of the shaft 75 and which half rotation is produced by a gear 77 loose from the shaft 75 and adapted to co-operate with a splined clutch member 78 normally retained 45 out of engagement with the clutch gear 77 by a cam 79 at one end of the shaft 63 above mentioned. The clutch gear 77 is rotated by a worm gear 80 which is driven by meshing miter gears 81, one of which is on the 50 shaft V.

It is not believed that any separate definition of the mode of operation of the machine will be required in order to make clear the performance and action of the mechanism, inasmuch as there has been hereinabove defined the performance of each member or feature of the machine, and the sequence in which these performances take place. It will be noted that the stock b is, 55 in the order mentioned, successively printed, numbered, perforated, reverse-side printed, provided with reinforcement tags or buttons, eyeleted, punched, trimmed or trimmed and perforated, and that the stock 60 so developed and transformed is cut into 65

separate tags or groups of tags and then initially stacked up upon the accumulator S and finally stacked up upon the stacker T, with the groups of tags or tag groups arranged upon the stacker with the eyeleted 70 ends staggered so that the final pile of stacked tags or tag groups is evenly built up and may be packed or stored away in even formation.

The entire operation is automatic and 75 without a halt, and the tags or tag groups are turned out with great rapidity and of uniform formation and perfection and with such variations of perforation, imprinting and numbering as may be desired. Obviously, any of the several means for printing, 80 numbering, and perforating, may be thrown out of operation as desired, as may also the eyeletting means P so that tags of various degrees of completion or of various nature, 85 when completed, may be produced upon the same machine by obvious and simple adjustments.

Having thus disclosed my invention, I claim and desire to secure by Letters Pat- 90

1. A machine of the character disclosed, comprising means for feeding tag stock, means for applying reinforcement material thereto at spaced points, means for puncturing the tag stock through the spaced reinforcement material, means for trimming the tag stock, and means for severing the tag stock into separate tag formations; means likewise being provided for applying eyelets to the tag stock at the reinforced portion thereof. 95

2. A machine of the character disclosed, comprising means for feeding tag stock, means for applying reinforcement material 100 thereto at spaced points, means for puncturing the tag stock through the spaced reinforcement material, means for trimming the tag stock, and means for severing the tag stock into separate tag formations; means likewise being provided for applying duplicate reinforcements to the tag stock in registration with the first mentioned reinforcements, means further being provided for applying eyelets to the tag 105 stock in registration with the first mentioned and duplicate reinforcements and for puncturing such duplicate reinforcements. 110

3. A machine of the character disclosed, comprising means for feeding tag stock, means for applying reinforcement material thereto at spaced points, means for puncturing the tag stock through the spaced reinforcement material, means for trimming the tag stock, and means for severing the tag stock into separate tag formations; means likewise being provided for applying eyelets to the tag stock at the reinforced portions thereof; each of said means including 120

a rotative member whereby the stock is subjected to successive action of rotative means.

4. A machine of the character disclosed, comprising means for feeding tag stock, means for applying reinforcement material thereto at spaced points, means for puncturing the tag stock through the spaced reinforcement material, means for trimming the tag stock, and means for severing the tag stock into separate tag formations; means likewise being provided for applying duplicate reinforcements to the tag stock in registration with the first mentioned reinforcements; means further being provided for applying eyelets to the tag stock in registration with the first mentioned and duplicate reinforcements and for puncturing such duplicate reinforcements; each of said means including a rotative member whereby the stock is subjected to successive action of rotative means.

5. In a machine of the character disclosed, means for feeding tag stock, means for applying eyelets thereto at spaced points, and cylinders between which the tag stock passes with the eyelets successively applied thereto, said cylinders being provided one with a die and the other with a punch for punching through tag stock in registration with the eyelet and for upsetting the material of the eyelet to clinch it to the tag stock.

6. In a machine of the character disclosed, means for feeding tag stock, means for applying eyelets thereto at spaced points, and cylinders between which the tag stock passes with the eyelets successively applied thereto, said cylinders being provided one with a die and the other with a punch for punching through tag stock in registration with the eyelet and for upsetting the material of the eyelet to clinch it to the tag stock; means, first being provided for applying reinforcement material to the tag stock at spaced points in registration with which the eyelets are applied to the tag stock, the punching of the tag stock being likewise produced through the reinforcement material.

7. In a machine of the character disclosed, means for feeding tag stock and means for applying reinforcement material to the same; said latter means comprising two cooperating cylinders which are jointly provided with means for applying reinforcement material to the tag stock, one of said cylinders being provided with means for temporarily retaining the reinforcement material thereon and transferring the same to the tag stock.

8. In a machine of the character disclosed, means for feeding tag stock and means for applying reinforcement material to the same; said latter means comprising two cooperating cylinders which are jointly

provided with means for applying reinforcement material to the tag stock, one of said cylinders being provided with means for temporarily retaining the reinforcement material thereon and transferring the same to the tag stock; means likewise being provided for supplying reinforcement material between said cylinders.

9. In a machine of the character disclosed, means for feeding tag stock and means for applying reinforcement material to the same; said latter means comprising two cooperating cylinders which are jointly provided with means for applying reinforcement material to the tag stock, one of said cylinders being provided with means for temporarily retaining the reinforcement material thereon and transferring the same to the tag stock; means likewise being provided for supplying reinforcement material between said cylinders, said cylinders being provided with further means for severing portions of said reinforcement material for transference to said tag stock.

10. In a machine of the character disclosed, means for feeding tag stock and means for applying reinforcement material to the same; said latter means comprising two cooperating cylinders which are jointly provided with means for applying reinforcement material to the tag stock, one of said cylinders being provided with means for temporarily retaining the reinforcement material thereon and transferring the same to the tag stock; one of said cylinders being provided with air ducts leading through the periphery thereof and at the outlets of which said reinforcement material is applied to such cylinder, further means being provided for producing suction within one of said air ducts and pressure within another thereof.

11. In a machine of the character disclosed, means for feeding tag stock and means for applying reinforcement material to the same; said latter means comprising two cooperating cylinders which are jointly provided with means for applying reinforcement material to the tag stock, one of said cylinders being provided with means for temporarily retaining the reinforcement material thereon and transferring the same to the tag stock; means being further provided for applying adhesive material to the reinforcement material prior to the application thereof to the tag stock.

In testimony whereof, we have signed our names to this specification in the presence of two subscribing witnesses.
